UNITED STATES PATENT OFFICE.

LEONARD JOSEPH FROHN, OF LYNNBROOK, NEW YORK.

SHEET FEEDER.

Application filed February 28, 1922. Serial No. 539,869.

To all whom it may concern:

Be it known that I, LEONARD JOSEPH FROHN, a citizen of the United States, and a resident of Lynbrook, in the county of 5 Nassau and State of New York, have invented certain new and useful Improvements in Sheet Feeders, of which the following is a specification, reference being made to the accompanying drawings, forming a part thereof.

My invention relates to certain improvements in sheet-feeding machines for automatically separating and feeding successive sheets of paper to printing, folding or ruling machines, or to other types of machines which are devised thereafter to operate on such sheets.

The objects of my invention are, among other things, chiefly to improve and simplify the various mechanisms required to properly separate and continuously feed the successive sheets, preferably from a fanned-out bank of paper, automatically and with great rapidity. To this end I have devised a continuous front edge feeder which will separate and advance the sheets in a continuous flow by mechanisms operating on the front portion of the sheets, such sheet forwarding mechanism being controlled by the steady advance of the front margins of the pile or bank of paper.

A further feature of my invention is to embody a suction feed-wheel for continuously feeding the sheets forwardly in a sheet-feeder of the "continuous" type, and to provide in such feeder automatic mechanisms which will ensure a constant supply of paper to be acted upon by this suction wheel.

Another feature is to provide a novel pile detector which will operate independently of the suction feed-wheel, and also independently of the number or timing of the sheets advanced thereby, so as to inaugurate the action of the bank or pile feed devices whereby the paper sheets may be advanced and maintained at the proper thickness beneath the feed-wheel which operates on the front margins of such sheets.

A further object of my invention is to provide a novel form of adjustable pile-drag which may be set at different positions to bear on the rear margins of the fanned-out sheets on the top of the pile, and is constructed and arranged above the feed-table to bear on the top and subjacent sheets with

a variable spring pressure so as to maintain the rear edges of the top sheets in proper alignment with a light yet firm pressure which will not interfere with the proper continuous feeding of the sheets.

A further object of my invention is to embody in such improved sheet-feeder means for holding the front edges of the topmost sheets to arrest their forward feeding when the suction is cut off from the suction feed-wheel thereby stopping the forwarding of the sheets.

My improved sheet-feeder also embodies other features of novelty and improvement whereby the various operating mechanisms are simplified and made more effective and otherwise better adapted for use, all of which will be hereinafter described and particularly pointed out in the appended claims.

The drawings show my invention in its preferred embodiment in a continuous sheet-feeder; my improvements, however, are not to be restricted to any particular type of sheet-feeder, since the invention may be embodied in various forms of sheet-feeders with the same advantages and results.

Of the drawings, Fig. 1 is a front view looking from the left in Fig. 2 certain parts of the feeder being omitted;

Fig. 2 is a sectional view on the line 2—2 of Fig. 1 in which parts of the sheet-detector mechanism have been omitted for the sake of clearness;

Fig. 3 is a fragmentary sectional view taken on the line 3—3 of Fig. 5 showing a portion of the stop mechanism for controlling the operation of the bank feed devices;

Fig. 4 is a detail view partly in section showing the stop mechanism locked in operative position;

Fig. 5 is a fragmentary sectional view taken on the line 5—5 shown in Fig. 1, and illustrating the detector mechanism in its position when no sheets are in the feeder;

Fig. 6 is a fragmentary sectional view showing the detector mechanism when the feeder is operating normally when the bank or pile of sheets under the suction feed-wheel is of the proper thickness;

Fig. 7 is a fragmentary sectional view showing the stop-rod as having been moved by its cam-controlled mechanism when the detector wheel lowers upon the pile of sheets becoming depleted and less than the required thickness beneath such detector wheel.

Fig. 8 is a view similar to Fig. 7 showing

the check-rod on the ratchet-pawl arm, as it will appear when the stop-rod is moved to the left to allow the operation of the ratchet mechanism;

5 Fig. 9 is a diagrammatic view showing the pawl-carrying ratchet arm as having been rocked to advance the bank feed belts;

Fig. 10 is a fragmentary detail view showing the mechanism to control the operation 10 of the stop rod;

Fig. 11 is a diagrammatic side elevation of the feeder showing particularly the coacting feed belts for the upper supply table and lower feed table;

15 Fig. 12 is an enlarged plan view showing the pile drag for the bank of sheets before the suction feed-wheel; and

Fig. 13 is an enlarged sectional detail view 20 of the pawl which engages the ratchet for moving the feed belts on the lower feed table.

Similar numerals refer to similar parts throughout the various figures.

Referring to Fig. 11, the upper loading 25 board or supply table 14 is supported by standards 15 to the side frames 16. A series of feed belts 17 travel over pulleys 18 and 19 and extend over the surface of the supply table 14 and around the drum 20 mounted 30 on the shaft 21 to gradually feed forward the bank of sheets loaded on such supply table 14. The lower feed-table 22 is attached to the frames 16, and a series of feed-belts 23 (Fig. 12) pass over pulleys 24 and 25 35 mounted on shafts 26 and 27 respectively journaled in the frame, said belts 23 extending over the upper surface of the feed-table 22 to advance the bank or pile of sheets to the sheet feeding and separating devices. 40 The drum 20 is rotatable in the frame 16, and serves to transfer the bank of sheets from the supply table 14 to the feed-table 22. The drum 20 is revolved in the direction shown by the arrow by a train of gears 45 driven from the gear 28 secured on the shaft 26. To hold the sheets close to the drum 20 while being reversed from the table 14 to the table 22, I have devised a series of spaced apart endless tapes 29 which pass around 50 the pulley 24, drum 20, and pulleys 30, 31, and 32, the pulley 32 being journaled in the rock-arm 33 to act as a tension device for the tapes by the force of the spring 34 coiled about the sliding rod 35 pivoted to 55 the arm 36 which spring normally tends to depress the rock-arm 33 with the pulley 32 to take up any slack in the tapes 29. The shaft 27 carries the ratchet 37 by which the feed-belts 23 are intermittently advanced 60 over the feed-table 22 to carry the bank of fanned-out sheets to the feeding devices.

In the present embodiment the sheet feeding and separating devices comprise a suction feed-wheel 38 having a perforated rim 39 which wheel is mounted on the shaft 40.

The ends of the shaft 40 are journaled in the side frames 16 as shown, and the wheel 39 is driven by gear 41 secured to the shaft 40. The gear 41 enmeshes with the idler gears 42 and 43 (Figs. 1 and 11), the gear 43 engaging the gear 44 on the lower feed roll shaft 45. The gear 44 enmeshes with the idler gear 46 which engages the gear 47 secured to the power shaft 48 which is driven by the belt 49 and pulley 50 from any suitable source as shown in Figs. 1 and 11. The suction mouth-piece 51 rests on the inner face of the perforated rim 39, and is connected to the transverse suction tube 52 by the pipe 53. The required suction to operate 75 the wheel 38 is applied to the tube 52 by any suitable means not shown. The sheets adhere to the perforated rim 39 of the wheel 38 during the rotation of the latter, and are taken off by the upper feed roll 54 journaled on the arm 55 mounted on the shaft 40, and the lower feed-roll 56 secured to the rotating shaft 45. The front edges of the sheets are kept separated by a blast of air 80 from the nozzle 57 mounted on the pipe 58 adjustably secured to the bracket 59 and connected with any suitable air pump not shown, after such sheets pass over the guide-plate 60 mounted on brackets 61 secured to the tie rod 62 as shown in Figs. 1 and 2; 85 also affixed to the rod 62 are the horizontally bent guide-fingers 63 extending forwardly from the guide plates 60 to the lower feed-roll 56 to support the sheets as shown in Fig. 2. Mounted to the transverse shaft 64 journaled in the guide-plates 60 are the oscillatable hold-back fingers 65 which are normally depressed into their full line position as shown in Figs. 1 and 2, but are raised into the path of the advancing sheets to engage the front edges of the sheets by the oscillation of the shaft 64 through the arm 66 secured to one end of the shaft 64 (Fig. 1), which arm is connected by the link 67 to the lower end of the hand-lever 68 pivoted at 90 69 to the frame 16 as shown in Fig. 2. Also pivotally secured to the lower end of the lever 68 is the link 70 connected to the arm 71 which actuates the oscillating valve 72 in the tube 52 which is thereby opened to 95 atmosphere, and immediately cuts off the suction from the mouth-piece 51 rendering the wheel 38 ineffective. By shifting the hand-lever 68 the pressman can simultaneously discontinue the feeding of the sheets 100 by the suction wheel 38 and also raise the hold-back fingers 65 to the dotted line position shown in Fig. 2 to prevent the forward margins of the front sheets from advancing 105 beyond the air-blast nozzle 57. 110

The pile detector mechanism which controls the bank feed independently of the action of the suction wheel 38 is best shown in Figs. 1, 3, 5 and 6, and comprises the detector roll 73 pivoted on the end of the 115

rock-arm 74 above one of the guide-plates 60 from which it is normally separated by the interposed front margins of the bank or pile of sheets 75 as shown in Fig. 5. The 5 rock-arm 74 is mounted on the pin 76 affixed to the bracket 77 secured to the bracket 78 carried by the tie rod 79 as shown in Fig. 3. The roll 73 is normally depressed in transverse alignment with the suction 10 wheel 38 by the spring 80 coiled about the rod 81 pivotally secured to the rock-arm 74, the upper end of the rod 81 passing through a slot in the bracket 82 mounted on the pin 76 as shown in Figs. 3, 5 and 6. Projecting 15 upwardly from the pin 76 and secured to the rock-arm 74 is the rock-finger 83, the tip 84 of which is adapted to oscillate in the slot 85 cut in the collar 86 formed in the bracket 78. The collar 86 supports a sliding stop- 20 rod 87 on which the sleeve 88 is adjustably secured by the split collar 89. The collar 86 has the circular recess 90 cut therein about the sliding stop-rod 87 (Fig. 3) to permit of the transverse reciprocation of the 25 rod 87 and sleeve 88 when the tip 84 of the finger 83 is partially withdrawn from the slot 85, or from the position shown in Figs. 3 and 6 to that shown in Fig. 5. Referring more particularly to Figs. 1 and 10, the rod 30 87 is normally being pressed to the left against the finger tip 84, as shown by the arrows in Figs. 7 and 10 by the spring 91 coiled about the rod 92 which is pivotally secured to the rock-arm 93 pinned to the 35 bracket 94 affixed to the frame 16. The free end of the rod 92 slides through the bracket 95 on the top of the frame 16 (Fig. 1). The right hand end of the rod 87 is supported in the bracket 96 affixed to the frame 16 having the horizontal bore 97 within which 40 the rod 87 is held and reciprocated. The rock-arm 93 adjustably carries the block 98 which is affixed to the rod 87 by any suitable means such as a set-screw (not shown). 45 The rod 87 is held from moving to the left by the finger 83 engaging the sleeve 88 when the pile of sheets 76 is of sufficient thickness to hold the finger tip 84 against the sleeve 88 on the rod 87 as shown in Fig. 6. However, when the pile of sheets becomes depleted 50 the detector-roll 73 is lowered by gravity and the spring 80 so as to swing the finger 83 to the left (Figs. 5 and 6), which releases the stop-rod 87 which will be moved to the left by the spring 91 when the cam-roller 99 on the rock-arm 93 falls into the drop 100 of the cam 101 secured to the constantly 55 rotating shaft 40.

Referring more particularly to Figs. 7-10, the right-hand end of the stop-rod 87 coacts with the upper end of the check-rod 102 which slides in the bore 103 formed at right angles with the bore 97 in the bracket 96. This check-rod 102 is pinned at 104 to the arm 60 105 of the bell crank lever 106 pivoted on the shaft 27. Depending from the pin 104 is the rod 107 which slides through the bracket 108 secured to the frame 16; between the bracket 108 and the collar 109 adjustably secured to the rod 107 is the spring 70 110 coiled about the rod 107. The arm 105 of the lever 106 carries the cam-roller 111 to engage with the cam 112 secured to the shaft 40. The cams 101 and 112 are so keyed relatively to each other on the shaft 40 that 75 the roller 99 falls into the drop 100 of the cam 101 when the rod 87 is released, just before the roller 111 would reach the end of the dwell of the cam 112 to enter the drop 113 of this cam. The arm 114 of the lever 80 106 carries at its end the rocking pawl 115 mounted on the stud 116 which pawl is adapted to engage the ratchet 37. Fig. 2 shows the position of the pawl 115 when the roller 111 is held out of the drop of the 85 cam 112 with the spring 110 under compression; Fig. 9 shows the pawl 115 retracted in a clockwise direction by the release of the spring 110 when the check-rod 102 slides upwardly through the bore 103 and bore 90 97 as shown in Fig. 8. Referring to Fig. 13 the stud 116 has two flat surfaces 117 and 118 cut therein about the pawl 115 forming the apex 119; the tail of the pawl 115 is formed with a bore 120 within which the 95 sliding pin 121 is yieldingly mounted by the spring 122 coiled about the shank 123. When the pin 121 bears on the apex 119, the pawl 115 is free to ride over the teeth of the ratchet 37; when the tail of the pawl is 100 depressed so as to allow the pin 121 to engage the surface 118, the pawl is held out of engagement with the ratchet which allows the shaft 27 to be rotated by the operator to advance or retract the feed belts 23 with the ratchet 37 free from its operating pawl. 105

My improved pile drag to bear with a firm yet variable pressure of the fanned-out bank of sheets is shown in Figs. 2, 11 and 12: The tie rod 124 is secured in the frames 110 16 and adjustably carries the rearwardly-projecting rod 125 which may be mounted on the rod 124 by a set-screw 126 and bracket 127 (Fig. 2) in any convenient manner so as to lengthen or shorten the rod 125 according to the length of the particular sheets composing the bank or pile 75. The rear end of the rod 125 carries the bracket 128 to which is secured the cross-rod 129, and mounted on the rod 129 are pairs of 115 forwardly projecting spring fingers 130 of different lengths to bear on the rear edges of the uppermost sheets as shown in Fig. 12. Preferably the pair of middle fingers 131 are the longest (to bear on the topmost sheet), and the length of the other pairs are progressively shortened outwardly from the rod 125, the outermost pair 132 being the shortest. The object of having the separate pairs of spring fingers of different lengths 120 125 130

is to provide a pile drag which will exert variable pressure on the topmost sheets, the pressure of the outer fingers 132 exerting the maximum pressure because of their relatively small resiliency when compared with the gradually increasing resiliency as the length of the fingers increases, the minimum pressure being exerted by the fingers 131 on the topmost sheet of the pile. By this form of pile drag the rear margins of the fanned-out bank of sheets are firmly held by a variable pressure so as to preserve the proper transverse alinement of the sheets on the feed-table 22.

15 The operation of my sheet-feeder is substantially as follows: When the suction-wheel 38 is normally feeding the sheets from the fanned-out bank 75, the roll 73 is held in the position shown in Fig. 6 with the finger tip 84 in engagement with the stop-rod 87 as shown in Fig. 3 and the sleeve 88 in close contact with the finger-tip 84 to prevent the movement to the left of the rod 87 under the force of the coil spring 91. The right end 20 of the rod 87 therefore engages the upper end of the check-rod 102 as shown in Figs. 1 and 2, and the bell lever 106 is held in the position shown in Fig. 2 with the spring 110 under compression and the cam-roller 111 25 riding only on the dwell of the cam 112. However when the feed-wheel 38 has separated the top sheets of the bank, and the thickness of the bank is thereby diminished so that it is necessary to advance the bank 30 or pile by moving the feed-belts 23 on the feed-table 22 and also the belts 17 on the table 14, the detector-roll 73 is then lowered by gravity and the spring 80 so as to swing the finger 83 to the left (Fig. 5), releasing the rod 87 which will move to the left when the cam 101 revolves so as to allow the roller 99 to be forced into the drop 100 by the spring 91 as shown in Fig. 10. This movement of 35 the stop-rod 87 in the direction of the arrows in Figs. 7 and 10 simultaneously allows the check-rod 102 to lift as shown in Fig. 8 under the force of the spring 110 thereby rocking the lever 106 in a clockwise direction as shown in Fig. 9 so as to allow the cam-roller 111 to enter the drop 113 of the cam 112 40 and the pawl 115 to be drawn backwardly over the teeth of the ratchet 37; when the lever 106 is rocked in an anti-clockwise direction by the cam-roller 111 riding out of the drop of the cam 112, the ratchet 37 will 45 advance the feed-belts 23 to forward the bank of sheets. This bank-feed movement through this pawl and ratchet mechanism will be repeated with each revolution of the cams 101 and 112 until the thickness of the fanned-out bank 75 beneath the suction wheel 38 and the detector-roll 73 has raised the latter so that the finger-tip 84 will re-engage the rod 87 and sleeve 88 (Fig. 3) to 50 hold the stop-rod 87 in its right hand posi-

tion with the cam roller 99 out of engagement with the drop of the cam 101, so as to prevent the reciprocation of the check-rod 102 (Fig. 4) which will swing the bell-lever 106 to the left as shown in Fig. 2 with the cam-roller 111 riding only on the dwell of the cam 112.

Whenever the operator wishes to stop the action of the suction feed-wheel 38 he shifts the hand-lever 68 which cuts off the suction connection to the rim 39 through the mouth-piece 51 by operating the valve 72, which thereby opens the interior of the tube 52 to atmospheric pressure, and at the same time lifts the hold-back fingers 65 from their full line to the dotted line position shown in Fig. 2 to prevent the sliding of the forward edges of the sheets over the guide fingers 63 to the bite of the feed-rolls 54 and 56. No means are provided to prevent overlapping of the fed-off sheets beyond the range of the fingers 65, because the leading edges of such sheets are not advanced by the action of the suction-wheel 38 beyond the range of the fingers 65 when raised.

The foregoing constructions embody the principles of my invention, but various changes may be made in the structural details without departing from the scope of my improvements. However the foregoing is sufficient to disclose the underlying principles and advantages of my invention as applied to a continuous sheet-feeder.

I claim as my invention:

1. In a sheet-feeder, a feed-table, means for advancing a bank of fanned-out sheets along said table, and constantly rotating suction-feeding devices operating on the front top portion of the bank for separating and forwarding the successive sheets.

2. In a sheet-feeder, a feed-table means for intermittently advancing a bank of fanned-out sheets along said table, and constantly rotating suction-feeding devices operating on the front top margin of the bank for separating and forwarding the successive sheets.

3. In a sheet-feeder, a feed-table, means for advancing a fanned-out bank of sheets along said table, and a rotary suction feed-wheel operating on the front portion of the bank for separating and forwarding the successive sheets.

4. In a sheet-feeder, a feed-table, means for intermittently advancing a fanned-out bank of sheets along said table, and a rotary suction feed-wheel operating on the front margin of the bank for separating and forwarding the successive sheets.

5. In a sheet-feeder, a feed-table, means for advancing a bank of fanned-out sheets on said table, rotary suction-feeding devices located over the front margin of the bank for continuously separating the successive sheets, and means actuated by the

depletion of the bank for controlling the operation of said advancing means.

6. In a sheet-feeder, a feed-table, means for intermittently advancing a bank of fanned-out sheets on said table, sheet-feeding devices operating on the front margin of the bank for continuously separating the successive sheets, and means actuated by the depletion of the bank for controlling the 10 operation of said advancing means.

7. In a sheet-feeder, a feed-table, means for advancing a bank of fanned-out sheets on said table, rotary suction-feeding devices operating on the front portion of the 15 bank for separating and forwarding the successive sheets, and means continuously resting on the bank and actuated by the depletion of the bank adjacent said feeding devices for controlling the operation of said 20 advancing means.

8. In a sheet-feeder, a feed-table, means for intermittently advancing a bank of fanned-out sheets on said table, rotary suction-feeding devices operating on the front margin of the bank for separating and forwarding the successive sheets, and means continuously resting on the bank and actuated by the depletion of the bank beneath and in alinement with said feeding 25 devices for controlling the operation of said 30 advancing means.

9. In a sheet-feeder, a sheet support, a suction-feeding off device arranged above said support, means for applying suction to said device, sheet-holding means located at the front edge of the support and normally out of the path of the fed-off sheets, and means for shutting off the suction and moving 35 said sheet-holding means into the path 40 of the sheets.

10. In a sheet-feeder, a sheet support, a suction-feeding off device arranged above said support, means for applying suction to said device, sheet-holding located at the 45 front edge of the support and normally out of the path of the fed-off sheets, and means for simultaneously shutting off the suction and moving said sheet-holding means into the path of the sheets.

50 11. In a sheet-feeder, a sheet support, a suction-feeding off device arranged above said support, means for applying suction to said device, a series of rock-fingers located at the front edge of the support and normally out of the path of the fed-off sheets, and means for shutting off the suction and moving said fingers into the path of the sheets.

55 12. In a sheet-feeder, a sheet support, a suction-feeding off device arranged above said support, means for applying suction to said device, a series of rock-fingers located at the front edge of the support and normally out of the path of the fed-off sheets, 60 and means for simultaneously shutting off

the suction and moving said fingers into the path of the sheets.

65 13. In a sheet-feeder, a sheet support, a suction-feeding off device arranged above said support, means for applying suction to 70 said device, a series of rock-fingers located at the front edge of the support and normally out of the path of the fed-off sheets, and manual means for simultaneously shutting off the suction and moving said fingers 75 into the path of the sheets.

14. In a sheet-feeder, a sheet support, a suction-feeding off device arranged above said support, means for applying suction to said device, a series of normally-depressed 80 rock-fingers located at the front edge of the support and out of the path of the fed-off sheets, and means for shutting off the suction and raising said fingers into the path of said sheets.

85 15. In a sheet-feeder, a sheet support, a suction-feeding off device arranged above said support, means for applying suction to said device, a series of normally-depressed rock-fingers located at the front edge of 90 the support and out of the path of the fed-off sheets, and means for simultaneously shutting off the suction and raising said fingers into the path of said sheets.

95 16. In a sheet-feeder, sheet-feeding devices for continuously separating the successive sheets, means for advancing a bank of fanned-out sheets to the feeding devices, and means controlled by the thickness of the bank below said devices and operable 100 independently of the action of said sheet-feeding devices for actuating said bank-advancing means.

105 17. In a sheet-feeder, sheet-feeding devices for continuously separating the successive sheets, means for advancing a bank of fanned-out sheets to the feeding devices, and means controlled by the thickness of the bank below said devices and operable 110 independently of the action of said sheet-feeding devices for intermittently actuating said bank-advancing means.

115 18. In a sheet-feeder, sheet-feeding devices for continuously separating the successive sheets, means for advancing a bank of fanned-out sheets to the feeding devices, and means for actuating said bank-advancing means operable independently of the number or timing of the successive sheets fed off the bank, but controlled by the thickness of the bank below said sheet-feeding devices.

125 19. In a sheet-feeder, sheet-feeding devices for continuously separating the successive sheets, means for advancing a bank of fanned-out sheets to the feeding devices, and means for actuating said bank-advancing means operable when the thickness of the bank below said devices is below a pre- 130 determined point.

20. In a sheet-feeder, sheet-feeding devices for continuously separating the successive sheets, and means for advancing a bank of fanned-out sheets to the feeding devices, and means for actuating said bank-advancing means operable when the thickness of the bank below the sheet-feeding devices is below a predetermined point.
21. In a sheet-feeder, sheet-feeding devices for continuously separating the successive sheets, means for advancing a bank of fanned-out sheets to the feeding devices, and means for actuating said bank-advancing means operable when the thickness of the bank below said devices is below a predetermined point and placed in inoperative position when the bank below said feeding-off devices is restored to its predetermined thickness.
- 20 22. In a sheet-feeder, sheet-feeding devices for continuously separating the successive sheets, and means for advancing a bank of fanned-out sheets to the feeding devices, and means for actuating said bank-advancing means operable when the thickness of the bank below the sheet-feeding devices is below a predetermined point and placed in inoperative position when the bank below said feeding-off devices is restored to its predetermined thickness.
23. In a sheet-feeder, a feed-table, means for advancing a bank of fanned-out sheets along said table, rotary suction-feeding devices acting on the front top portion of the sheets for continuously separating and feeding the successive sheets from the bank, and means for inaugurating the action of said sheet-advancing means when the thickness of the bank below said feeding devices is less than a predetermined point irrespective of the number or timing of the successive fed-off sheets.
24. In a sheet-feeder, a feed-table, means for advancing a bank of fanned-out sheets along said table, a rotary suction feeding-wheel acting on the front top margin of the sheets for separating and forwarding same from the bank, and means independent of the action of said feeding wheel for inaugurating the action of said bank-advancing means when the thickness of the bank below said feeding wheel is less than a predetermined point.
25. In a sheet-feeder, a feed-table, means for advancing a bank of fanned out sheets along said table, a rotary suction-feeding wheel acting on the front top margin of the sheets for separating and forwarding same from the bank, and means resting on the bank and in alinement with said feeding wheel for inaugurating the action of said bank-advancing means when the thickness of the bank below said feeding wheel is less than a predetermined point.
- 65 26. In a sheet-feeder, a feed-table, means for advancing a bank of fanned out sheets along said table, a rotary suction-feeding wheel acting on the front top margin of the sheets for separating and forwarding same from the bank, and means adjacent to, but independent of the action of, said feeding wheel for inaugurating the action of said bank-advancing means when the thickness of the bank below said feeding wheel is less than a predetermined point.
27. In a sheet-feeder a unitary pile-drag to rest on a bank of sheets having separate pairs of laterally spaced-apart resilient means bearing on the sheets.
28. In a sheet-feeder a unitary pile-drag to rest on a bank of sheets having a plurality of laterally spaced-apart resilient fingers bearing on the sheets.
29. In a sheet-feeder a pile-drag adjustably mounted to rest on a fanned-out bank of sheets and having a plurality of laterally spaced-apart resilient fingers bearing on the sheets on either side of its center.
30. In a sheet-feeder a pile-drag to rest on a bank of fanned-out sheets having sets of laterally spaced-apart resilient fingers bearing on the different sheets on either side of its center.
31. In a sheet-feeder a pile-drag to rest on a bank of fanned-out sheets having sets of resilient fingers of different lengths bearing on the different sheets on either side of its center.
32. In a sheet-feeder a pile-drag comprising separate laterally spaced-apart means to bear with a variable pressure on the rear margins of a fanned-out bank of sheets on either side of its center.
33. In a sheet-feeder a pile-drag comprising a plurality of laterally spaced-apart resilient fingers of different lengths symmetrically disposed on either side of its center to bear with a variable pressure on the rear margins of a fanned-out bank of sheets.
34. In a sheet-feeder a pile-drag comprising a plurality of pairs of laterally spaced-apart resilient fingers of different lengths symmetrically disposed on either side of its center to bear with a variable pressure on the rear margins of a fanned-out bank of sheets.
35. In a continuous sheet-feeder having an upper supply-table and a lower feed-table, coacting means for advancing a bank of fanned-out sheets along said tables, rotary suction feeding devices operating on the front portion of the bank on the feed-table for separating and forwarding the successive sheets, and means for actuating said bank-advancing means on both tables operable when the height of the bank beneath and in alinement with said feeding devices is below a predetermined point.
36. In a continuous sheet-feeder having an

upper supply-table and a lower feed-table, coacting means for simultaneously advancing a bank of fanned-out sheets along said tables, rotary suction feeding devices operating on the front portion of the bank on the feed-table for separating and forwarding the successive sheets, and means for actuating said bank-advancing means on both tables operable when the height of the bank adjacent said feeding devices is below a predetermined point.

37. In a continuous sheet-feeder having an upper supply-table and a lower feed-table, coacting means for simultaneously advancing a bank of fanned-out sheets along said tables, sheet-feeding devices operating on the front margin of the bank on the feed-table for continuously separating the successive sheets, and means for actuating said bank-advancing means on both tables operable when the height of the bank beneath and in alinement with said sheet-feeding devices is below a predetermined point, and rendered inoperative when the bank is restored to its predetermined height.

38. In a continuous sheet-feeder having an upper supply-table and a lower feed-table, coacting means for simultaneously advancing a bank of fanned-out sheets along said tables, sheet-feeding devices operating on the front margin of the bank on the feed-table for continuously separating the successive sheets, and means for actuating said bank-advancing means on both tables operable when the height of the bank adjacent said sheet-feeding devices is below a predetermined point, and rendered inoperative when the bank is restored to its predetermined height.

39. In a continuous sheet-feeder having an upper supply-table and a lower feed-table, coacting means for advancing a bank of fanned-out sheets along said tables, rotary suction-feeding devices operating on the front margin of the bank on the feed-table for separating and forwarding the successive sheets, and means for automatically actuating said bank-advancing means on both tables operable when the height of the bank beneath and in alinement with said feeding devices is below a predetermined point.

40. In a continuous sheet-feeder having an upper supply-table and a lower feed-table,

coacting means for simultaneously advancing a bank of fanned-out sheets along said tables, rotary suction feeding devices operating on the front margin of the bank on the feed-table for separating and forwarding the successive sheets, and means for automatically actuating said bank-advancing means on both tables operable when the height of the bank adjacent said feeding devices is below a predetermined point, and rendered inoperative when the bank is restored to its predetermined height.

41. In a sheet-feeder, a feed-table, means for advancing a bank of fanned-out sheets along said table, rotary suction-feeding devices operating on the front margin of the bank for separating and feeding successive sheets, means for actuating said bank-advancing means controlled by the height of the bank below said feeding devices, and means for automatically disengaging said actuating means from said bank-advancing means operable through the continued movement of the feeder.

42. In a sheet-feeder, a feed-table, means for advancing a bank of fanned-out sheets along said table, suction-feeding devices operating on the front margin of the bank for separating, and feeding successive sheets, means for actuating said bank-advancing means controlled by the height of the bank below said suction-feeding devices, and means for automatically disengaging said actuating means from said bank-advancing means operable through the continued movement of the feeder.

43. In a continuous sheet-feeder, a suction feed-wheel for advancing the sheets from the front top portion of the bank by applying suction continuously thereto.

44. In a continuous sheet-feeder, a suction feed-wheel for advancing the fanned-out sheets from the front margin of the bank.

45. In a continuous sheet-feeder, a rotary suction feed-device operating on the front top portion of the bank by applying suction continuously thereto for separating and advancing the successive sheets.

46. In a continuous sheet-feeder, a rotary suction feed-wheel operating on the front margin of the fanned-out bank for separating and advancing the successive sheets.

LEONARD JOSEPH FROHN.
